Filed Oct. 13, 1960, Ser. No. 62,474

Term of patent 14 years

(Cl. D26—5)

The FIGURE is a perspective view of the desk-type housing for a computing machine.

The rear wall is plain, and the side not shown is substantially a mirror image of the side shown.

The essential features of the design reside in the portions shown in full lines on the drawing.

We claim:

The ornamental design for a desk type housing for a computing machine, as shown and described.
